UNITED STATES PATENT OFFICE.

MICHEL S. YASSUKOVITCH, OF NEW YORK, N. Y.

ANTIFREEZING-HYDRANT.

1,270,677.

Specification of Letters Patent. Patented June 25, 1918.

Application filed December 20, 1917. Serial No. 208,101.

To all whom it may concern:

Be it known that I, MICHEL STANISLAUS YASSUKOVITCH, a subject of Russia, residing at New York, in the county of New York 5 and State of New York, have invented certain new and useful Improvements in Anti-freezing-Hydrants; and I do hereby declare the following to be a full, clear, and exact description of the invention, such as will 10 enable others skilled in the art to which it appertains to make and use the same.

The present invention relates to improvements in anti-freezing hydrants, in which provision is made for draining the water 15 from the water delivery stock when the valve which controls the passage of the water from the water service pipe, or main, to said stock is closed.

The present invention aims primarily to 20 drain off the water at a low point in the system by a simple and automatically operating device, and to incidentally remove to a separate stock provided for the purpose, the valve-actuating mechanism which was 25 heretofore located in the water delivery stock where it interfered with the free passage of the water, and caused a material reduction in the available pressure at the surface.

30 In the accompanying drawings forming a part of this application, and in which similar reference symbols indicate corresponding parts in the several views:

Figure 1 is a vertical sectional view of 35 an anti-freezing hydrant with associated parts partly shown in elevation, and constructed in accordance with my present invention.

Fig. 2 is an enlarged fragmentary sectional view of the water valve and draining device.

Fig. 3 is a vertical sectional view with 45 parts shown in elevation, showing the draining device applied to a different type of valve and illustrating a different form of plug.

Fig. 4 is an enlarged fragmentary sectional view of the valve and draining device shown in Fig. 3; and

50 Fig. 5 is an enlarged plan view of the plate for holding the drain pipe.

Referring more particularly to the drawings, 1 designates the usual water delivery stock which may be connected to the up-standing plug 2, as appears in Fig. 1, or

to the sunken plug 3, shown in Fig. 3; and 4 represents the connection or elbow usually employed to place the stock 1 in communication with the service or water supply main 5.

In accordance with the present invention the water valve 6 and its operating mechanism 7 are removed from the water delivery stock 1, and are placed respectively in a valve casing 8 included at a convenient 60 point in the service or main 5, and in a separate stock 9 near to or remote from the water delivery stock 1, as conditions render advantageous. Access may be had to the valve operating mechanism 7 through the 65 cover plate 10 at the surface.

The effect of the new locations given the water valve 6 and its operating mechanism 7 is to leave the stock 1 free from obstacles to the passage of the water in great volume 75 and at high pressure, and furthermore allows of placing the water valve 6 at a lower location than was heretofore possible; which allows the water from the stock 1 and connection or elbow 4, to drain completely 80 therefrom through an opening 11 which I provide for this purpose in the lower part of the water valve 6. When the valve 6 is finally closed this opening 11 will remain just above the lower part 12 of the 85 valve seat, and will afford free egress to all of the water remaining in the stock 1 and elbow 4.

Figs. 1 and 2 show the application of the invention to a hollow cone valve 6; while 90 in Figs. 3 and 4 the invention is shown applied to a double-disk expanding gate valve 13.

Referring now first to Figs. 1 and 2, the draining device is represented in the form 95 of a conduit or pipe 14, which is attached to and moves with the valve 6, passing through a stuffing box 15 provided at the bottom of a depression 16 in the valve casing 8. One means of connecting the drain 100 pipe 14 with the valve 6 consists in boring and threading the lower end of said valve, as is illustrated at 17 in Fig. 2, and in placing therein two spaced and perforated disks 18 and 19 which loosely imprison therebetween a third disk 20 fixed in any desired manner to the upper end of drain pipe 14.

A plug 21 is employed to close the lower 110 end of the pipe 14, and a perforation or eduction port 22 is made therein at a suit-

able elevation to deliver the water to a trough 23 which conveys it away from the valve casing.

Referring in detail to Fig. 4, the drain pipe 14 is held to move with the valve 13 by a plate 24, which is provided, as more particularly appears in Fig. 5, with elongated slots 25 and 26 at its ends. Screws 27 and 28 engage through said slots 25 and 26 and are threaded into the disks of the valve 13. This construction allows the disks of the valve 13 to expand and contract in the usual manner, and at the same time provides a convenient means for carrying the drain pipe 14.

The operation of the invention is the same in either form of the constructions described, and may be briefly described as follows:

20 The water valve is normally closed, as shown in Fig. 3, in which position it entirely cuts off the supply of water to the stock 1 and plug above. When water is desired the cover 10 of the stock 9 is first 25 removed and a proper implement engaged with the valve operating mechanism 7, by which the valve may be opened to the required degree. As the water valve is raised it draws the drain pipe 14 upwardly there- 30 with, the perforation or eduction port 22 being finally carried within the stuffing box 15, where it will be masked and the discharge of the water therethrough prevented. However, when the water valve is opened 35 to a small degree only, for instance as shown in Fig. 1, the perforation 22 will remain unmasked and will permit the escape of a small quantity of water that may seek its way through the opening 11 in said valve. 40 This amount of water will be small, but it will exert a cleansing action on the interior of the valve and drain pipe 14.

When the supply of water is discontinued by the closing of the valve 6, all of the 45 waste water in the stock 1 and elbow 4 may pass through the drain opening 11 into the hollow interior of the valve body and thence may flow directly downward through the pipe 14 and out through the eduction port 22.

50 It will be apparent to all those skilled in the art that although I have described the invention in connection with gate valves for hydrants, the improved device is applicable to other valves and other systems.

55 It is obvious that the details of construction and arrangement of parts may be varied without departing from the spirit of my invention, and therefore I do not wish to be limited to such features except as may 60 be required by the claims.

I claim:

1. The combination with an underground water service pipe, a stock for delivering water to the surface, and a connection between said water service pipe and stock, of

a hollow valve for controlling the passage of water to said connection and stock, said valve having an opening through which the water in said stock and connection may pass to the hollow interior thereof, and a drain pipe detachably suspended from and movable with said hollow valve, substantially as described.

2. The combination with an underground water service pipe, a stock for delivering water to the surface, and a connection between said water service pipe and stock, of a hollow valve for controlling the passage of water to said connection and stock, said valve having an opening through which the water in said stock and connection may pass to the hollow interior thereof, a drain pipe having its open upper end in free communication with the hollow interior of said valve, means whereby said drain pipe is detachably suspended from said valve so as to move therewith, said drain pipe having an eduction port for the escape of the water, and means whereby said eduction port may be closed, substantially as described.

3. The combination with an underground water service pipe, a stock for delivering water to the surface, and a connection between said water service pipe and stock, of a hollow valve for controlling the passage of water to said connection and stock, said valve having an opening through the side thereof through which the water in the stock and connection may pass to the interior thereof, a drain pipe having its open upper end disposed in communication with the lower part of the hollow interior of said valve, means whereby said pipe is loosely suspended from said valve and caused to move therewith, the lower end of the drain pipe being closed and an eduction port provided in the side thereof, and a stuffing box slidingly receiving said drain pipe and adapted to mask said eduction port, substantially as described.

4. The combination with an underground water service pipe, a stock for delivering water to the surface, and a connection between said water service pipe and stock, of a hollow valve for controlling the passage of water to said connection and stock, said valve having an opening through which the water in said stock and connection may pass to the hollow interior thereof, said valve also having a threaded bore in its base opening into the hollow interior thereof, a pair of spaced perforated disks screwed into said bore, a third perforated disk of a smaller diameter loosely imprisoned between said first-named disks, a drain pipe having its open upper end attached to and supported by said third loose disk, said pipe having an eduction port, and means whereby said port may be closed, substantially as described.

5. The combination with an underground water service pipe, a stock for delivering water to the surface, and a connection between said water service pipe and stock, of 5 a hollow valve controlling the passage of water from said service pipe to the connection and stock, said valve having a drain opening in the side thereof which when the valve is closed occupies a position substantially 10 on a level with the lowest point in said connection whereby all of the water in said stock and connection may be allowed to pass through said opening and into the interior of said valve when the latter is closed, and a 15 drain pipe having its open upper end in communication with the bottom of the hollow interior of said valve, said open upper end being disposed close to the lower part of said drain opening whereby to quickly 20 carry off all of the waste water passing into the valve interior, substantially as described.
6. The combination of a water service pipe, a water delivery stock, a connection between said pipe and stock, a valve for 25 controlling the flow of water from the pipe to the stock, a second stock, mechanism contained in said second stock for operating said valve, said valve having a drain opening therein arranged to be at a level substantially 30 even with the lowest point in said connection when said valve is closed, a drain pipe detachably carried by and movable with said valve and having its upper end disposed near to the lower part of said 35 drain opening whereby to receive the waste water therefrom, said drain pipe having an eduction port, and means whereby said port may be closed, substantially as described.
7. The combination of a water service 40 pipe, a stock, a connection between said pipe and stock, a valve adapted to control the passage of water from the pipe to the con-

nexion and stock, said valve having a drain opening arranged to lie at a level substantially as low, as the lowest point in said connection when the valve is closed, a drain pipe having its upper open end disposed near to the lower part of said drain opening to receive waste water therefrom, means for detachably connecting said pipe to said 45 valve, a stuffing box slidingly receiving said pipe, said pipe having an eduction port in its side adapted to be masked in said stuffing box only when said valve is in the full open position but to be free thereof when the 50 valve is closed or partly opened to permit the discharge of water, substantially as described.

8. The combination of a water service pipe, an unobstructed stock, an elbow connecting said pipe and stock, a hollow valve adapted to control the flow of water to said elbow and stock, a second stock, valve-operating mechanism in said last named stock, said valve having a drain opening arranged 60 to be at a level substantially as low as the lowest point in said elbow when the valve is closed to allow all of the water in said stock and elbow to drain out, a drain pipe fitted through the bottom of said valve and 65 having a water receiving opening arranged below the lower part of said drain opening, means for detachably and loosely connecting said pipe to said valve, a stuffing box slidily receiving said pipe, said pipe having 70 an eduction port in the side thereof adapted to be masked in said stuffing box when the valve is fully open but to be free thereof when the valve is closed or partly open, and a removable plug fitted in the lower end 75 of said drain pipe, substantially as described.

In testimony whereof, I affix my signature.

MICHEL S. YASSUKOVITCH.
